CALCULATING MACHINE

Robert L. Muller, Detroit, Mich., assignor to
 Burroughs Adding Machine Company, Detroit,
 Mich., a corporation of Michigan

Application September 22, 1934, Serial No. 745,066
 Renewed August 7, 1936

15 Claims. (Cl. 197—128)

This application relates to a calculating machine, and particularly to the paper handling equipment of such a machine. It is a continuation-in-part of my copending application, Serial No. 469,957, filed July 23, 1930.

5 The machine is of the type known as a "front-feed" machine, that is, in addition to a platen which is adapted to hold a record sheet on which a large number of entries may be made, it has 10 a "front-feed throat" that may be opened and closed to permit work sheets to be inserted in front of the platen, printed upon, removed, and new work sheets inserted, while the record sheet remains in the machine.

15 In the machine of said copending application provision is made not only for automatically opening the front-feed throat, but also for automatically closing it. The present application includes certain improvements as will hereinafter 20 appear.

The general object of the invention is to provide an improved paper handling equipment for calculating machines and the like.

A more particular object is to provide an improved 25 front-feed paper equipment for such machines having a throat that may be automatically closed and opened during a cycle of machine operation.

A still further object is to provide an improved 30 front-feed machine in which the throat may be automatically closed and opened during a single cycle of machine operation and in any columnar position of the carriage at the option of the operator.

35 Other objects and advantages of the invention will appear from the following specification and drawings.

An embodiment of the invention is shown in the accompanying drawings in which:

40 Figure 1 is a left side elevation and partial section of a machine with the improved paper handling equipment applied thereto, the parts being in normal or "closed-throat" position.

Fig. 2 is a partial right side elevation and section of the platen mounting and the front-feed 45 throat, with the parts shown in "open-throat" position.

Fig. 3 is a view similar to Fig. 2 with the parts in "closed-throat" position.

50 Fig. 4 is a partial rear elevation with some of the parts cut away to show others more clearly, the parts being in normal "closed-throat" position.

Fig. 5 is a detail front elevation of a portion of 55 the automatic throat opening and closing mecha-

nism, the parts being shown in normal "closed-throat" position.

Fig. 6 is a view similar to Fig. 5 but showing the parts in "open-throat" position.

Fig. 7 is a partial front elevation of another 5 species of throat opening and closing mechanism with the parts in normal "closed-throat" position.

Fig. 8 is a partial front elevation of still another 10 species of throat opening and closing mechanism, the parts being in normal "closed-throat" position.

Fig. 9 is a detail view of one of the carriage 15 studs used with the species of Fig. 7.

Fig. 10 is a partial side elevation of the tabulating mechanism for the paper carriage.

Fig. 11 is a partial rear elevation of said tabulating mechanism.

Fig. 12 is a partial right side elevation of the 20 machine showing a species of the invention in which the control of the opening and closing of the throat is by a special motor bar on the machine.

Fig. 13 is a partial rear elevation of the automatic mechanism for opening the throat as used 25 with the construction of Fig. 12.

The invention is shown applied to a Burroughs 30 calculating machine of the type used for book-keeping, accounting, and statistical work. Since the general features of this machine are well 35 known, it will be described only very generally.

General features of machine

The machine, which is illustrated generally in 35 Fig. 1, is of the type which, after it is properly conditioned, is given a cycle of operation during which its various functions are performed. It may be cycled by a hand crank but most of the present-day machines are cycled by a power operated driving means which is actuated by an electric motor 8 acting through a clutch contained in the housing 9. The motor and clutch are normally controlled by a motor bar S which, when depressed, causes the motor to give the machine a cycle of operation. The motor employed 40 may be of the normally inactive type in which the motor circuit is closed by depression of the motor bar or may be a continuously running motor. When the machine is given a cycle of operation by the motor, a drive shaft 60 is rotated through 45 a single revolution, said shaft being connected by suitable cranks, links and levers, some of which are shown in dotted lines in Fig. 1, to a main shaft 17 of the machine.

An amount indexing means is provided com- 50

55

prising a plurality of depressible amount keys 1 upon which items may be indexed for entry into the machine. Suitable calculating mechanism, including a registering mechanism (not shown) is contained in the housing 3. Numerous function-control keys, one of which is the total key 2 (Fig. 1), are provided for controlling the various functions performed by the machine.

The machine has a printing mechanism for printing the amounts entered in it as well as the totals thereof, a portion of said printing mechanism being shown at 4 in Fig. 1. Normally, at an appropriate time during the machine cycle, generally near the end of the first half of the cycle, the printing mechanism is operated to drive the type against record material held about a platen P.

Provision is made for enabling printing to occur in different columns on record material supported by said platen. This is accomplished by means of a columnar-printing control means in the form of a traveling paper carriage 5 together with means for moving and controlling the movement of said carriage. This carriage, which supports the platen P, is urged across the machine to the left, viewing the machine from the front, by a spring drum 18 and its movement is controlled by a tabulating mechanism that will be described later. Normally, near the end of each machine cycle, the carriage moves from one column to another. This movement may be from one column to a column immediately adjacent or it may be to some other column, the control being variable. The carriage is arrested by tab stops 122 shown in Figs. 1, 10, and 11 whose operation will be later described. These stops are freely adjustable so that the stationary position of the carriage and the width of the columns may be readily changed. When it is desired that the paper carriage remain stationary, the tabulating mechanism is normalized or disabled by means of a "carriage normal" key 6 (Fig. 1) the use and function of which are well known. This "carriage normal" key may also be made a "live" key, i. e., its depression may cause the motor to give the machine a cycle of operation in which event it is called a "vertical spacing bar," as also well known.

The carriage may be returned to the right by hand or it may be returned by a motor through mechanism contained in the housing 7.

The machine may be conditioned to perform various functions either manually by the function-control keys above mentioned or automatically under the control of the paper carriage which, in its movement to different positions, conditions the machine for various functions as it well known in the art.

Platen mounting

The platen P is not only mounted so that it may rotate for line spacing but also so that it may be moved from its normal printing position adjacent the printing mechanism to an "out-of-printing" position which may also be called a "throwback," or "front-feed," position to facilitate the removal and insertion of work sheets as presently will be explained. In the embodiment disclosed the platen may be moved to two different "throwback" positions, one of which is called a "partial" or "intermediate-throwback" position and the other the "full-throwback" position.

The platen P (Fig. 2) is fixed to a platen shaft 10 that is journaled for rotation in two end plates 11, one of which is shown in Fig. 2, and

both of which are pivoted on a shaft 12 that is supported by the paper carriage end plates 13. The platen is urged to the printing position of Fig. 2 by its own weight and by a spring 14 (Fig. 1).

Associated with the platen are flexible strips 15 adapted to hold a record sheet R around the platen so that said sheet will move with the platen as the latter is moved from printing to front-feed position and vice versa without having its position disturbed. Suitable line-space mechanism is provided for the platen, portion 16 of which are shown in Fig. 1.

The platen is rocked from its printing position of Fig. 3 to its front-feed position of Fig. 2 by rocking the shaft 12 clockwise in Fig. 2. This rocking is accomplished by means of crank arms 20 of which there is one near each end of the shaft 12. One of these arms is shown in Fig. 2 and the other in Fig. 1. The crank arms 20 carry studs 21 operating in slots 22 of levers 23 pivoted on studs 24 on the end plates 13 of the paper carriage. These slots are curved so that when the parts are in the position of Fig. 2 the platen is latched in printing position due to the fact that the studs 21 are in such position in the slots 22 that any tendency of the platen to move out of printing position is resisted by such studs engaging the rear edges of the slots. The rear ends of the levers 23 are connected by a bail 30 member 25 by means of which the levers are rocked as will be presently described.

When the levers 23 are rocked counterclockwise (Fig. 2), that is, when their rear ends are raised, the crank arms 20 are moved clockwise which results first, in unlatching the platen and, then, as the studs 21 engage the upper curved end of the slots 22, in moving the platen from printing to front-feed position. When the levers 23 are rocked in the opposite direction the platen is returned to printing position.

Front-feed

The paper carriage supports a "front-feed means" for enabling work sheets to be front fed with respect to the platen into a front-feed throat that may be opened and closed. This "front-feed means" may include portions of the paper equipment other than the main throat elements but, for the present, the description will be directed primarily to the main throat elements.

A front-feed throat is formed by the platen P and a set of feed, or pressure, rolls 30 (Fig. 2) that cooperate with the platen. Provision is made for causing a relative movement between the platen and pressure rolls to open and close the front-feed throat.

The pressure rolls 30 are carried by a shaft 31 journaled in the ends of arms 32 pivoted at 33 on the plates 11 in which the platen shaft 10 is journaled. The feed rolls are urged into engagement with the platen by springs 34 of which one is shown in Fig. 2, the springs being connected between the arms 32 and the plates 11. It should be noted that while the pressure rolls may be moved relative to the platen they move with it as it is moved from printing to front-feed position and vice versa.

The arm 32 shown in Fig. 2 has an upwardly extending portion 35 carrying a stud 36 that is positioned to engage an abutment nose 37 on a lever 38 pivoted at 39 to one of the carriage side plates 13. When the front-feed throat is closed the parts occupy the position illustrated in Fig. 3.

The front-feed throat is opened by raising the bail 25 upwardly from its Fig. 3 position. This rocks the levers 23 counterclockwise and swings the platen from the position of Fig. 3 toward that of Fig. 2. As the platen moves upwardly and rearwardly the arms 32 carrying the pressure rolls 30 move bodily with the platen and, as the platen approaches its front-feed position, the stud 36 on arm 35 engages the abutment nose 37. Further movement of the platen toward front-feed position then causes the arm 35 to be rocked counterclockwise which swings the feed or pressure rolls 30 away from the platen while, at the same time, the platen continues its movement away from the pressure rolls. In this way the front-feed throat is quickly and widely opened as the platen reaches its front-feed position.

The front-feed throat is closed by moving the bail 25, which movement is controlled in a manner to be presently described. If the bail is free for downward movement the levers 23 will be rocked clockwise and the platen moved from its Fig. 2 toward its Fig. 3 position by the urge of springs 14 (Fig. 1) and by gravity. The initial movement of the platen causes the stud 36 to move away from the abutment nose 37 and allows the spring 34 to move the pressure rolls into engagement with the platen to grip the inserted work sheet. This occurs very quickly at the start of the movement of the platen and before such movement disturbs the position of the work sheet. The work sheet is thus gripped while the platen is in its raised or front-feed position and the papers are then carried with the platen as the latter moves to front-feed position.

In said copending application, the platen is latched in front-feed position, and the throat in open position, by a latch 40 shown in dotted lines in Fig. 2, said latch hooking over a stud 41 on lever 23. The latch is released by a manually operated bell crank lever 42 having a cam edge 43 adapted to engage a stud 44 on latch 40 to release it. Lever 42 also has a cam slot 45 operating on a stud 46 on the lever 38 which carries the abutment nose 37. When the lever 42 is rocked counterclockwise the arm 38 with its abutment nose 37 is moved to release the arm 35 to permit the feed rolls to grip the work sheet. Continued movement of lever 42 releases the latch 40 and allows the platen to move to printing position. The manually operated portion of the lever 42 has been shown in dotted lines in Fig. 2 as has also the platen latch 40 because neither of these parts is used in the present embodiment, shown in Figures 7, 8, and 13 of the present application. But they have been illustrated because a portion of lever 42 is used in all of the embodiments of the present application and the parts shown in dotted lines also are used in the embodiments shown in Figures 4, 5, and 6.

Front-feed paper table or chute

In order to guide a work sheet under the platen from the front and into the open front-feed throat, a suitable paper table, or paper chute, is provided which is constructed, and which operates, as follows:

The table or chute has a flat, sheet-metal bottom 50 and upstanding side edges 51. These side edges are pivoted on a shaft 52 so that the chute can rock from a "sheet-receiving" position shown in Fig. 2 to a "printing," or "sheet-holding," position such as shown in Fig. 3.

When the parts are in the position of Fig. 2,

a record sheet R may be placed about the platen and held in position by the holding strips 15. A work sheet W may then be placed on the paper chute 50, and guided under the platen from the front and into the front-feed throat which is open. The sheet is placed in the proper line-space position relative to the printing line of the platen and collated relative to the record sheet by a Burroughs line finder which is well known and which has not been illustrated. The front-feed throat is then closed to grip the inserted work sheet and the platen is moved to printing position.

As the front-feed throat is closed and as the platen moves to printing position, the platen shaft 10 engages a cam edge 53 on the lower part of the side edges 51 of the paper chute and cams the table from the position of Fig. 2 to that of Fig. 3, that is, from "sheet-receiving" to "sheet-holding" or "printing" position. As the chute moves to this position it swings the unfed end of the work sheet W rearwardly about the platen, the lower edge 54 of the chute serving as a paper engaging or holding means that acts in this capacity. The bottom plate 50 of the chute 25 also assists in holding the work sheet in position. These parts assist in holding the sheet in feeding relation to the platen.

Power means for opening and closing front-feed throat

The front-feed throat may be automatically opened and closed, and the platen may be automatically moved from printing to front-feed position and vice versa, by and under the control of a power means as will now be described.

Referring to Fig. 1, the motor 8 that gives the machine cycles of operation also drives, through the clutch 9, a shaft 60, the arrangement being such that, when the motor gives the machine a cycle of operation, the shaft 60 is rotated one revolution in a clockwise direction (Fig. 1). Fixed to the shaft 60 is a snail cam 61 that operates against a stud 62 carried by a lever 63 pivoted at 64 on a machine bracket. Connected to the forward end of lever 63 is one end of a spring 64 whose other end is connected to a stationary arm 65. The rear end of lever 63 is connected by a link 66 to a member 67 which is slidably mounted (Figs. 5 and 6) on a stationary plate 68 at the rear of the machine.

In the form of the invention shown in Figs. 5 and 6, the upper end of the slide 67 has an arm 70 pivoted thereto and urged counterclockwise by a spring 71. The upper end of arm 70 carries a roller stud 72 adapted to engage the underside of the bail 25 on the traveling paper carriage. The arm 70 is normally prevented from turning under the influence of spring 71 by means of a latch 73 slidably mounted on slide 67 and urged upon and into engagement with a shoulder on arm 70 by means of spring 74.

Provision is made for latching the slide 67 in its lower position illustrated in Fig. 5, and, for this purpose, a latch 75 is provided which is pivoted to the stationary back plate 68 and urged clockwise by a spring 76. The upper end of this latch carries a pivoted passby pawl 77 adapted to be engaged by studs 110 and 111 on the bail 25. This latch normally engages in a notch 78 in slide 67 as shown in Fig. 5.

Referring again to Fig. 1, the normal position of the cam 61 is as shown, with the low part of the cam immediately below the stud 62. In Fig. 1 the parts are illustrated in the position they

occupy with the slide 67 latched against upward movement as shown in Fig. 5, which accounts for the fact that the stud 62 is not in engagement with the cam. It will be appreciated that, if the latch 75 (Fig. 5) is released, the slide 67 is free to move upwardly which it does under the urge of spring 64 (Fig. 1) which has been tensioned by the cam 61 as will be presently described. The latch 75 is released by the lateral movement of the traveling paper carriage and in order that the operation may be clear we will briefly explain the sequence of operations.

Assume that the machine is given a cycle of operation with the parts in the position of Fig. 1 except that the lever 63 is in a position such that the stud 62 contacts the low portion of the cam 61 as shown in dotted lines. As the machine is given a cycle of operation the cam 61 rotates clockwise. This cam is shaped so that it moves the lever 63 to the position of Fig. 1 after the cam has made less than a half revolution and prior to the period in the cycle of operation of the machine in which the printing mechanism operates. In other words, during the initial portion of the machine cycle, the spring 64 is tensioned, the lever 63 is rocked counterclockwise, and the slide 67 is drawn downwardly to the position of Fig. 5 where it may be latched by the latch 75. During the latter part of the cycle of machine operation the paper carriage is tabulated to its next columnar position and, assuming that there is a stud 110 positioned on the bail 25 so as to be operative during this movement, it will be clear that, during the latter part of a cycle of machine operation, the latch 75 will be released, whereupon the slide 67 will be moved upwardly by the spring 64 and the bail 25 pushed upward to move the platen from printing to front-feed position and to open the front-feed throat, where the bail 23, 25 and the parts moved thereby are held by the latch 40 engaging the stud 41 until the latch 40 is retracted from the stud 41 by manipulation of finger piece 42.

In the form illustrated in Figs. 5 and 6, provision is made for disabling the effective connection between the slide 67 and the bail 25 after the slide has moved the bail upwardly to move the platen and open the throat. As previously explained, the arm 70, which is pivoted on the upper end of slide 67 is urged counterclockwise by spring 71 and this arm is normally prevented from moving counterclockwise by a latch 73. This latch has a laterally projecting arm 80 adapted to engage a stud 81 on the stationary plate 68. Near the upper limit of the movement of the slide 67 the projection 80 engages the stud 81 and prevents the latch 73 from moving further with the slide 67. This releases the arm 70 whereupon the spring 71 swings the arm counterclockwise out of engagement with the bail 25. This frees the bail for downward movement so that, if the platen is released, as, for example, by hand, it will be free to move to printing position without interference from the slide 67 and arm 70.

The arm 70 is restored to its normal Fig. 5 position as the slide 67 is lowered. As the slide is lowered it pulls the arm 70 downwardly and a stud 82 (Fig. 4) on the arm engages the inclined edges of a slot 83 in stationary plate 68 (Fig. 4) and rocks the arm against the tension of the spring 71 so that the parts are returned to the Fig. 5 position.

Thus it will be clear that the power for throwing back the platen and opening the front-feed

throat is derived from the motor driving means during a machine cycle and independently of any traveling movement of the paper carriage. The power is applied somewhat indirectly by being momentarily stored in the spring mechanism. This indirect application is advantageous in that it gives a range of adjustment as to the time when the power may be applied. For example, the power is stored during the first part of the cycle and is then available for use at any time during the latter half of the cycle or after the cycle has ended.

It is to be noted that, in the operation just described, the platen is automatically moved to front-feed position and the front-feed throat is opened by power under control of the paper carriage. Provision is made, however, for both closing and opening the front-feed throat completely automatically and by power.

Automatically closing and opening the front-feed throat during a cycle of machine operation

Referring to Fig. 5, it will be observed that the slide 67 has a lower notch 85 in it for receiving the latch 75. Likewise, it will be noted, that the bail 25 carries a stud 111 positioned slightly higher than the stud 110. The parts are proportioned so that, as the carriage tabulates when the stud 111 is active, the latch 75 will be released only momentarily because stud 111 passes quickly over the end of pawl 77. The result is that, instead of allowing the slide 67 to move upwardly to the full extent of its movement, the latch 75 will enter the notch 85 and arrest the slide in an intermediate position such as shown in Fig. 6. This position is such that the lateral lug 80 on the latch 73 has not yet engaged the stud 81, and the pivoted arm 70 is not released but remains in engagement with the bail 25 (Fig. 6). The upward movement of the slide 67, although only a partial upward movement, moves the bail 25 upwardly and moves the platen P away from its printing position. Also, the movement of the bail 23, 25 is not sufficient to enable the latch 40 to engage above the stud 41 to latch the parts in the position to which they have been moved.

It will be recalled that the tabulation of the carriage occurs during the latter part of a cycle of machine operation. Accordingly, during the latter part of a cycle of machine operation in which the carriage moves so that the stud 111 becomes active, the platen will be automatically moved away from printing position although it will not be moved to the position heretofore described. As long as the roller stud 72 on arm 70 remains in engagement with the bail 25, the platen cannot be returned even though it be released. But, during early part of the next cycle of machine operation, the slide 67 is returned downward to its normal position and hence the bail 25 is released to permit the platen to return to printing position.

This partial movement of the platen is not sufficient to open the front-feed throat in the manner heretofore explained, but provision is made for automatically opening the throat in the following manner.

As shown in Figs. 3 and 4, the paper carriage supports a bail 90 carried by arms 91 pivoted at 92 and urged clockwise, as viewed in Fig. 3, by a spring 94. The movement of the bail in a clockwise direction is normally limited by a stud 95 on a slide 96 held in the position of Fig. 5 by a spring 97, these parts being some of

those used in connection with the skip tabulating mechanism described in Rinsche Patent 1,580,534.

Mounted on the bail 90 which travels with the paper carriage is an adjustable cam 98 (Fig. 5) positioned so that, at the time the upper stud 111 releases the latch 75, the cam 98 engages the stud 95 on slide 96, with the result that the bail 90 is cammed upwardly. This bail has an extension 99 at its right hand end as shown in Fig. 4 which is positioned under a vertically movable slide 100 best shown in Fig. 3. When the bail 90 is moved upwardly the slide 100 is also moved upwardly and a lateral lug 101 on the upper end of the slide moves into the path of a stud 102 on the upper end of an extension 103 of the left hand feed roll arm 32, as viewed from the front of the machine, which arm carries the feed roll shaft 31. This movement of the parts occurs before the platen moves away from printing position. As the platen moves away from printing position, the feed roll shaft moves with it and because the arm 103 is blocked by the stud 102 engaging the lug 101, the arms 32 are caused to turn counterclockwise which moves the feed rolls 30 away from the platen to open the front-feed throat.

When the platen moves back to printing position the feed rolls 30 are of course released to close the front-feed throat and the slide 100 moves back to normal as soon as the cam 98 passes the stud 95.

With this construction, it will be understood that, when the paper carriage moves to a predetermined columnar position, the platen will be moved to an intermediate front-feed position and the front-feed throat automatically opened. The operator may then remove one work sheet and insert another, after which he may enter an item on the amount keys and give the machine a cycle of operation by depressing the motor bar. As the machine operates, the cam 61 (Fig. 1) will, during the initial part of the cycle, move the lever 63 to draw the slide 67 downwardly to release the bail 25. This causes the front-feed throat to be automatically closed and the platen to be returned to printing position which action occurs prior to operation of the printing mechanism during the cycle of machine operation.

In the operation just described the platen is moved to intermediate front-feed position and the throat opened during the latter part of one cycle of operation of the machine and then, during the first part of the next cycle, the throat is automatically closed and the platen returned to printing position. However, when a stud 110 is positioned on the bail 25 as illustrated in Fig. 5, the front-feed throat may be automatically closed during the first half of a cycle of operation of the machine and then automatically opened during the latter half of the same cycle, or, in other words, the front-feed throat may be both opened and closed during a cycle of machine operation. For example, assume that the stud 111 has operated during a cycle and that the front-feed throat is open and the platen is in its intermediate front-feed position. The parts would be in this position at the beginning of the cycle of machine operation that is now to be considered. During the first part of this cycle the front-feed throat will be closed and the platen returned to printing position. A printing operation will then occur and, during the latter half of this same machine cycle, the carriage will be tabulated to a new columnar position. During this movement of the carriage,

the stud 110 becomes active to release the slide 67 whereupon the front-feed throat will be opened and the platen moved to front-feed position.

It is to be understood that the last-mentioned opening of the throat and movement of the platen could be to the "intermediate" position if, instead of using a stud 110, one of the studs 111 were located on the bail at the appropriate point. 10

Closing and opening front-feed throat automatically while carriage remains stationary

Provision is also made for closing and opening the front-feed throat, and for moving the platen 15 from printing to front-feed position and vice versa, with the carriage stationary.

Ordinarily, the paper carriage is tabulated during the latter part of each cycle of machine operation and the carriage thus moves from column 20 to column across the machine until it reaches its final column whereupon the carriage return mechanism may be set into operation by hand, or automatically, to return the carriage to a predetermined position. With the construction 25 heretofore described, it is possible to close the throat automatically in any columnar position of the carriage and, either allow it to remain closed for the next column, or automatically open it for the next column, depending upon the arrangement of the stops 110 and 111. 30

It is sometimes desirable, however, to be able to both close and open the throat automatically during each machine cycle and provision has been made for quickly and easily converting the 35 present mechanism into one that will operate in this manner.

While this closing and opening may take place during operations of the machine in which the carriage is tabulated, it is preferably done while 40 the carriage remains stationary. The carriage may be held stationary by disabling the tabulating mechanism by depressing the "carriage normal" key 6 shown in Fig. 1. Or said tabulating mechanism may be automatically disabled when 45 the carriage reaches a predetermined position as presently will appear.

Portions of the tabulating mechanism are illustrated in Figs. 10 and 11. Mounted in a stationary part of the machine is a tabulating abutment 50 120 having an abutment face 121. The paper carriage carries a plurality of tab stops 122 which engage this abutment face in the different columnar positions of the carriage. These tab stops are carried by a rod 123 (Fig. 1) which is rockable to enable the stops to be raised above the abutment face 121. The spacing of the stops 122 on the rod 123 determines the columns at which the carriage will stop. The carriage is released to move from one columnar position to another 55 by swinging the rod 123 to free the active stop 122 from the abutment. Mounted on the back plate of the machine is a slide 124 carrying a stud 125 engaged by a member 126 that is oscillated during each cycle of operation of the machine by a cam 127' (Fig. 1). Pivoted on the slide 124 (Fig. 11) is pawl 127 whose upper end is adapted to engage under the tab stops 122. As the member 126 together with slide 124 is moved downwardly (Fig. 11) during the first part 60 of a cycle of operation of the machine, the pawl 127 is moved downward to a position where it can engage under the tab stop 122 that is against the abutment 121. Upon the return, or upward, movement of the slide 124, 65

which takes place during the latter part of a cycle of machine operation, the pawl lifts the tab stop so that the carriage is free for movement to the next column under the influence of the usual carriage spring. As the carriage moves, the tab stop 122 moves off the top of the pawl 127 and the shaft 123 is rocked back to normal so that the next tab stop 122 can engage the abutment. As this stop moves to position, it engages the side edge of pawl 127 and moves it clockwise as viewed in Fig. 11 until the stop brings up against the abutment face 121. In this manner, the carriage is automatically tabulated from column to column during cycles of operation of the machine to cause printing to occur in different columns on the paper supported by the carriage.

This tabulating mechanism may be automatically disabled as follows: Referring to Fig. 11, a bell crank lever 130 is pivoted on the abutment 120 at 131, said lever being urged counterclockwise against a limit stud 132 by a spring 133. This bell crank has a lower arm adapted to engage a stud 134 on the pawl 127. The bell crank also has an upper cam nose 135 adapted to contact the undersides of the tab stops 122. As one of the tab stops 122 moves to position against the abutment 120, its underside engages the cam nose 135 and rocks the lever 130 clockwise so that its lower arm is out of contact with the stud 134, thus freeing the tabulating pawl 127 for normal operations.

A special tab stop 122' has been provided in one column. This stop is shown adjacent the abutment 120 in Fig. 11. A normal tab stop 122 is shown to the right. This special tab stop is similar to the normal stops except that it is cut away at 136 as illustrated in Figs. 10 and 11. When the special tab stop moves against the abutment 120, its lower surface is high enough so that it does not move the bell crank 130 with the result that the bell crank holds the pawl 127 in the position of Fig. 11 where it is out from under the tab stop 122 and will not engage the latter to raise it as the machine is given a cycle of operation. The result is that in this column the carriage will remain stationary until it is released by some other means.

Release means has been provided under the control of the total key. Referring to Fig. 1 it will be observed that the total key 2 is carried by a bell crank 140 connected to a link 141 carrying a stud 143 adapted to engage one end of a pivoted lever 144. The other or rear end of this lever, contacts a lateral lug 145 on a bell crank lever 146 (Fig. 11) which is connected by a link 147 to a stud 148 on the bell crank 130. When the total key is depressed the bell crank 146 is rocked clockwise as viewed in Fig. 11 and the link 147 is thrust to the left. This rocks the bell crank 130 clockwise and releases the pawl 127 for normal movements. The result is that, if the total key is depressed and the machine is given a cycle of operation, the carriage will be tabulated to the next column near the end of the cycle of operation.

The number of special tab stops 122' used can be varied to suit the requirements and they can be located in any desired column or columns. In the embodiment shown, the special tab stop is located in the last column just before the carriage is to return. The result is that, when the total key is depressed, and the machine given a cycle of operation, the carriage moves slightly to the left and then is automatically returned by the automatic carriage return mechanism.

Referring now, to Fig. 7, it will be observed that the roller 72, which engages the bail 25 in connection with opening and closing the front-feed throat, is carried by an integral extension of a slide 150 similar to the slide 67 heretofore described. There is no pivoted arm on the upper end of this slide. Instead the roller 72 is carried directly by the slide. The slide 67 shown in Figs. 1, 5 and 6 can also be used by fixing the arm 70 securely to the slide so that the arm will not turn. A latch 151 is provided for this slide, said latch being pivoted at 152 and urged clockwise by a spring 153.

The machine may be converted into one that will close and open the front-feed means automatically during each machine cycle by disabling the latch 151 (Fig. 7). This is preferably accomplished by means of a finger piece 154 that can be quickly and easily adjusted. Usually this is done when the carriage is held in a stationary position by depression of the "carriage normal" key or because the tabulating mechanism is automatically disabled.

When the machine is given a cycle of operation in this columnar position of the carriage, the slide 150 is pulled down during the initial part of the cycle in a manner heretofore explained. This releases the bail 25 and allows the platen to move from its front-feed to its printing position and causes the front-feed throat to be closed. The printing mechanism normally operates after the throat is closed. During the latter half of the cycle of machine operation, the high point of the cam 61 (Fig. 1) moves past the stud 62 and releases the lever 63. Since the lever is no longer latched by the latch 151, the slide 150 moves upwardly to open the front-feed throat and move the platen to front-feed position.

This automatic closing and opening will continue to take place during each machine cycle until the finger piece 154 is again moved to release the latch 151. Accordingly, during each machine cycle, and preferably with the carriage remaining stationary, the front-feed means may be moved from closed to open throat condition and vice versa during each cycle of machine operation and independently of any other manual or automatic control of the latch 151.

Completely automatic control of closing and opening front-feed throat in predetermined columns

In the form of the invention just described it is necessary for the operator to manually set the detent 150 in order to cause the machine to close and open the throat automatically while the carriage remains stationary. Provision is made, however, for conditioning the mechanism automatically without requiring any manipulation on the part of the operator.

To accomplish this result the tabulating mechanism is disabled automatically by the carriage when the carriage reaches a predetermined columnar position. The form of throat-opening means used is that shown in Figure 7 in which the operating slide 150 does not have a pivoted arm on its end. The adjustment of the tab stop 122 relative to the stud 110 for tripping the latch 151 that holds the slide 150 is such that the stud 110 does not pass the latch when the carriage reaches the predetermined columnar position. Assume that the carriage reaches this predetermined columnar position and that a stud 110 contacts the pawl carried by latch 151 and releases the slide 150. As the slide 150 moves up-

wardly it carries the bail 25 with it and the stud 110 moves above the end of the pawl on the latch 151. The latch then tends to return to its normal position under urge of spring 153 but cannot do so because the lower end of latch 151 engages the side edge of the slide 150. At the beginning of the next machine cycle the slide 150 is pulled downwardly and the bail 25 follows it. As the bail moves downwardly the stud 110 comes down with it and engages the pawl to retain the latch 151 in released position. The relative adjustment between the tab stop 122 and stud 110 must be such that the vertical line of movement of the center of the stud 110 is sufficiently to the side of the pawl so that when the bail descends and the stud 110 comes down it will engage the pawl to retain the latch in released position. The above operation having taken place during the first half of the cycle, the slide 150 is not latched by the latch 151 and the slide is free to move upward again. Nevertheless, it does not move upward immediately to open the throat because it cannot move until the high point of the snail cam 51 (Fig. 1) has passed the roller stud 62. This does not occur until after the printing mechanism has operated but when it does occur the slide 150 moves upwardly again to open the throat.

The above adjustment of the parts is not a fine adjustment. The above operation is obtainable throughout a substantial range of adjustments. In order to extend this range the pawl may be constructed as illustrated by the pawl 160 in Figure 8 when it is known that this type of carriage control is wanted. Referring to Fig. 8, the special pawl 160 is mounted on the upper end of the latch 151. This pawl has an inclined cam surface 161. The stud 110 that is used to obtain the control is made so that it can be enabled and disabled and it is numbered 162 in Figs. 8 and 9. It is mounted in the bail 25 so that it can be moved into and out of active position by finger pressure applied in one direction or the other, the stud being held in either of its positions by a spring clip or detent 165 (Fig. 9). This enables this particular automatic control by the carriage to be enabled or disabled quite easily.

The operation of the stud 162 and the pawl 160 is as above described. When the carriage moves into a position where the stud 162 contacts the pawl 160, the latch 151 is moved, whereupon the slide 150 moves upward. As it moves upward the bail 25 moves upward and the stud 162 moves with it. During the first half of the next machine cycle the slide 150 is pulled down, whereupon the bail 25 with the stud 162 moves downward. The stud contacts the cam edge 161 of the pawl 160 and maintains the latch 151 in released position so that the carriage will again open during the latter half of the machine cycle. The provision of the long cam surface 161 on the pawl 160 enables a rough adjustment to be made as between the tab stop 122 and the stud 162, because the vertical line of movement of the stud 162 can vary as long as it is such that the stud 162 will contact some part of the fairly long inclined cam surface 161 of pawl 160.

The front-feed throat is thus automatically closed and automatically opened during a single cycle of machine operation with the carriage stationary. The operator need pay no attention to setting a manipulative member such as the detent 164 heretofore explained.

With this form of the invention, when the total key is depressed, the condition of the machine

is changed. Depression of the total key enables the tabulating mechanism and when the carriage moves from the column where it has been, the latch 151 moves back to latching position. As shown, the total key is operative as described 5 when the carriage is in its last column. Accordingly, when the total key is depressed and the machine given a cycle of operation, the carriage moves slightly to the left during the latter part of the cycle and it is then returned automatically 10 to the right by the carriage return mechanism.

One of the studs 162 can, of course, be used when the tabulating mechanism is in tabulating condition. In such event, bail 25 is released at about the time the carriage is tabulating from 15 one column to another, or during the carriage movement. This speeds up the opening of the front-feed throat and the movement of the platen to front-feed position.

Closing and opening the front-feed throat automatically in any columnar position at the option of the operator

In another form of the invention, the operator, at his option, can cause the front-feed throat to 25 be automatically closed and then automatically opened during any cycle of machine operation and with the carriage stationary in any column that he chooses. In fact, the opening and closing of the throat is independent of the carriage. 30

Referring to Fig. 12, the machine is provided with a special motor bar 170 overlapping the regular motor bar. The stem 171 of the special motor bar is connected to one arm 172 of a pivoted bell crank lever whose other arm 173 carries a stud 174 bearing against an arm 175 fixed to a shaft 176. Fixed to this shaft is another arm 177 which is connected by a link 178 to a slide 179 shown best in Fig. 13. The upper end of slide 179 carries a passby pawl 180 adapted to 40 engage a stud 181 on a latch 182 pivoted at 183 and urged clockwise by a spring 184. This latch engages a shoulder 185 of a striking hammer 186 urged clockwise, as viewed in Fig. 13, by a spring 187. said striking member having a lug 45 188 adapted to engage the upper end of the latch 151.

When the special motor bar 170 is depressed, the regular motor bar is depressed and the machine given a cycle of operation. These two motor bars are latched down during the cycle by a latch 170^a (Fig. 12) but are released near the end of the cycle of machine operation. As the motor bar 170 moves downward, it rocks bell crank 172-173 and the connections 175, 176, 177, 178 55 move slide 179 downwardly. During this movement, the passby pawl 180 has no effect on the latch 182. But, when the motor bar is released, and the slide moves upwardly under the influence of a spring 189, the passby pawl rocks the 60 latch 182 counterclockwise to release the hammer 186 which is thereupon fired against the latch 151 to release the latter. Release of latch 151 allows the slide 150 to move upwardly to move the platen from printing to front-feed 65 position and to open the front-feed throat.

The hammer 186 is returned to normal by the upward movement of the slide 150. This slide carries a stud 190 adapted to engage the cam edge 191 of one arm of a bell crank 192 pivoted 70 to the stationary plate 68. The other arm of this bell crank has a slot 193 engaging over a stud 194 on the hammer member 186. As the slide 150 moves upward the bell crank 192 is rocked counterclockwise which rocks the firing 75

member 186 back to normal position where it is latched by the latch 182.

Assume that the carriage is in any column with the throat open and that the operator depresses the special motor bar 170. During the first part of the cycle of machine operation, the slide 150 is lowered and latched, which causes the throat to automatically close. After printing occurs, and during the latter part of the 10 cycle of machine operation, the hammer 186 strikes the latch 151 to release it, whereupon the slide 150 is automatically raised to open the throat.

The special motor bar can be depressed while 15 the tabulating mechanism is operative, in which event the opening of the throat occurs just before or during the carriage tabulation to the next column. The throat is thus opened after the printing mechanism has operated and before the carriage reaches its next column so that a fast operator can take out a work sheet while the carriage is moving to its next position.

Provision is made, however, for having depression of the special motor bar 170 also disable the 20 tabulating mechanism. Positioned under the arm 173 of bell crank 172-173 (Fig. 12) is a stud 200 on a slide 201 which is urged upward by a spring 202. The rear end of this slide has a stud 203 which operates in a cam slot 204 (Fig. 30 11) of a lever 205 pivoted at 206 to the machine back plate. Connected to lever 205 is a slide 207 which extends to the right in Fig. 11 to a position adjacent the tabulating mechanism. The right-hand end of this slide has a forked end 35 extending over stud 181 and a downwardly extending arm 198 which is adapted to engage the pawl 127.

The arrangement is such that, when the special 40 motor bar 170 is depressed, the slide 201 (Fig. 12) is moved downward and this moves the slide 207 (Fig. 11) to the right. This moves the pawl 127 out of the path of the tab stop 122 which is in position at the time so that, when the machine is given a cycle of operation, the carriage 45 is not tabulated but remains stationary.

The stud 200 is removable and, when it is desired to not have the tabulating mechanism disabled by the special motor bar, the stud is removed.

50 From the above, it will be clear that by depressing the special motor bar 170 the operator can cause a cycle of operation of the machine in which the carriage remains stationary and in which the front-feed throat is automatically closed and then automatically opened during said cycle of machine operation. The operator thus has the option of choosing the column in which the throat is to be automatically closed and opened.

60 If the motor bar should be depressed in a column where the throat is closed and the platen is in printing position, the result will be an automatic opening of the throat and an automatic movement of the platen to front-feed position 65 near the end of the cycle of machine operation. In other words, there will be an automatic opening of the parts without a closing and this can take place with the tabulating mechanism operative or inoperative.

70 It is to be understood that the structure shown is for purposes of illustration only and that modifications may be made therein without departing from the spirit and scope of the invention as defined by the appended claims.

I claim:

1. A calculating machine having means for giving it cycles of operation, a printing mechanism, a platen normally occupying a printing position relative to said printing mechanism but movable therefrom to an out-of-printing position, power means for moving said platen to its out-of-printing position, a traveling paper carriage normally movable from column to column during cycles of operation of said machine, and means conditionable by a single manipulative member and operable in any columnar position of said carriage to cause said carriage to remain stationary during the next cycle of machine operation and to condition said power means independently of the position of said carriage to cause it to automatically move the platen to out-of-printing position near the end of said next cycle of machine operation.

2. A front-feed machine of the class described having means for giving it cycles of operation, a printing mechanism, a platen, paper supporting means, a column printing control means for causing printing to occur in different columns on the paper supported by said supporting means, front-feed means for enabling a work sheet to be front-fed relative to said platen and for holding said sheet in printing position, said front-feed means being movable from a closed to an open-throat position and vice versa, power means for moving said front-feed means to open-throat position, and means conditionable by a manipulative member, with said column printing control means conditioned for printing in any column, for disabling said column printing control means and, independently of said column printing control means, to condition said power means to cause it to automatically move said front-feed means to open-throat position near the end of the next cycle of machine operation.

3. A front-feed machine of the class described having means for giving it cycles of operation, a traveling paper carriage normally moved from column to column across the machine during cycles of machine operation, a platen, front-feed means for enabling a work sheet to be front-fed relative to said platen and for holding said sheet in printing position, said front-feed means being movable from a closed to an open-throat position and vice versa, power means for moving said front-feed means to open-throat position, and means conditionable by a manipulative member and operable in any columnar position of said carriage to cause said carriage to remain stationary during the next cycle of machine operation and independently of said carriage to condition said power means to cause it to automatically move said front-feed means to open-throat position near the end of said next cycle of machine operation and while said carriage remains stationary.

4. A front-feed calculating machine having means for giving it cycles of operation, a printing mechanism normally operated at a predetermined time during a machine cycle, a platen normally occupying a printing position relative to said printing mechanism but movable away therefrom to a front-feed position to facilitate the removal and insertion of work sheets, power means normally operating during a machine cycle initiated with said platen in front-feed position, to cause said platen to be moved to printing position but not to be returned to front-feed position, and manipulative means for

readily conditioning said power means to cause it, during each subsequent cycle of machine operation without further manipulation of said manipulative means, to move said platen from front-feed to printing position prior to operation of said printing mechanism and to return said platen to front-feed position after said printing mechanism has operated.

5. A front-feed calculating machine of the class described having means for giving it cycles of operation, a printing mechanism normally operated at a predetermined time during a machine cycle, a platen normally occupying a printing position relative to said printing mechanism but movable away therefrom to a front-feed position to facilitate the removal and insertion of work sheets, power means normally operating, during a machine cycle initiated with said platen in front-feed position, to cause said platen to be moved to printing position but not to be returned to front-feed position, selective control means for causing said power means to move said platen to front-feed position at selected times, and means other than said selective control means for readily conditioning said power means to cause it, during each subsequent machine cycle and irrespective of said selective control means, to move said platen from front-feed to printing position prior to operation of said printing mechanism and to return said platen to front-feed position after said printing mechanism has operated.

6. A front-feed calculating machine of the class described having means for giving it cycles of operation, a printing mechanism normally operated at a predetermined time during a machine cycle, a platen, front-feed means for receiving and holding a work sheet in front-fed position relative to said platen, said front-feed means being movable from closed to open-throat condition and vice versa, power means normally operating, during a machine cycle initiated with said front-feed means in open-throat condition, to cause said front-feed means to be moved to closed-throat condition but not to be returned to open-throat condition, and manipulative means for readily conditioning said power means to cause it, during each subsequent machine cycle without further manipulation of said manipulative means, to move said front-feed means from open to closed-throat condition prior to operation of said printing mechanism and to return it to open-throat condition after said printing mechanism has operated.

7. A front-feed calculating machine of the class described having means for giving it cycles of operation, a printing mechanism normally operated at a predetermined time during a machine cycle, a platen, front-feed means for receiving and holding a work sheet in front-fed position relative to said platen, said front-feed means being movable from a closed-throat to an open-throat condition and vice versa, power means normally operating, during a machine cycle initiated with said front-feed means in open-throat condition, to cause said front-feed means to be moved to closed-throat condition but not to be returned to open-throat condition, selective control means for causing said power means to move said front-feed means to open-throat condition at selected times, and means other than said selective control means for readily conditioning said power means to cause it, during each subsequent machine cycle and irrespective of said selective control means, to

cause said front-feed means to move from open to closed-throat position prior to operation of said printing mechanism and to be returned to open-throat condition after said printing mechanism has operated.

8. A front-feed calculating machine of the class described having means for giving it cycles of operation, a printing mechanism normally operated at a predetermined time during a machine cycle, a traveling paper carriage supporting a platen, front-feed means for enabling a work sheet to be front-fed relative to said platen and for holding said sheet in front-fed position, said front-feed means being movable from a closed to an open-throat condition and vice versa but normally being in closed-throat condition, power means for moving said front-feed means, said power means normally being ineffective to move said front-feed means, and manipulative control means operable irrespective of the position of said carriage to initiate a machine cycle and to condition said power means to move said front feed means to open-throat position during said machine cycle irrespective of the position of said carriage.

9. A front-feed calculating machine of the class described having means for giving it cycles of operation, a printing mechanism normally operated at a predetermined time during a machine cycle, a traveling paper carriage supporting a platen, front-feed means for receiving and holding a work sheet in front-fed position relative to said platen, said front-feed means being movable from a closed to an open-throat condition and vice versa but normally being in closed-throat condition, power means for moving said front-feed means, said power means normally being ineffective to move said front-feed means, and manipulative control means for conditioning said power means to enable it, during the next machine cycle, which cycle is initiated while said front-feed throat is open and occurring while said carriage remains in the columnar position where said throat is open, automatically to move said front-feed means to closed-throat condition prior to operation of said printing mechanism and automatically to move said front-feed means to open-throat condition after said printing mechanism has operated.

10. A front-feed machine of the class described having means for giving it cycles of operation, a printing mechanism normally operated at a predetermined time during the machine cycle, a traveling paper carriage supporting a platen, said carriage normally being movable from one column to another during a machine cycle but being capable of being held stationary, front-feed means for receiving and holding a work sheet in front-fed position relative to the platen, said front-feed means being movable from a closed to an open-throat condition and vice versa but normally being in closed-throat condition, power means for moving said front-feed means, said power means normally being ineffective to move said front-feed means, and manipulative control means for causing said paper carriage to remain stationary during a machine cycle and for conditioning said power means to enable it to operate during a cycle of machine operation initiated with said front-feed throat open and while said carriage remains stationary, automatically to close said front-feed throat prior to operation of said printing mechanism and automatically to open said throat after said printing mechanism has operated.

11. A front-feed machine of the class described having means for giving it cycles of operation, a printing mechanism normally operated at a predetermined time during a machine cycle, a platen normally occupying a printing position relative to said printing mechanism but movable away therefrom to a front-feed position to facilitate the removal and insertion of work sheets, power means for moving said platen, said power means normally being ineffective for moving said platen, a device normally movable during each machine cycle, control means for said power means automatically governed by said movable device to cause said platen to be moved to front-feed position, and manipulative means operable at the option of the operator for conditioning said power means, independently of said automatic control, to enable said power means, during the ensuing machine cycle initiated with said platen in front-feed position, to cause said platen automatically to be moved to printing position prior to operation of the printing mechanism and to be returned to front-feed position after said printing mechanism has operated.
12. A front-feed machine of the class described having means for giving it cycles of operation, a printing mechanism normally operated at a predetermined time during a machine cycle, a traveling paper carriage supporting a platen normally occupying a printing position relative to said printing mechanism but movable away therefrom to a front-feed position to facilitate the removal and insertion of work sheets, power means for moving said platen, said power means normally being ineffective to move said platen, and manipulative means operable at the option of the operator to condition said power means independently of any movement of, or position of, said carriage to enable said power means to operate, during the ensuing machine cycle initiated while said platen is in front-feed position, to cause said platen to be moved to printing position prior to operation of said printing mechanism and to be returned to front-feed position after said printing mechanism has operated.
13. A front-feed calculating machine of the class described having means for giving it cycles of operation, a printing mechanism normally operated at a predetermined time during a machine cycle, a platen, front-feed means for receiving and holding a work sheet in front-fed position relative to said platen, said front-feed means being movable from a closed to an open-throat condition and vice versa, power means for moving said front-feed means, said power means normally being ineffective to move said front-feed means, a device normally moved during each machine cycle, means controlled by said movable device for automatically controlling said power means to move said front-feed means to open-throat condition, and a manipulative means operable at the option of the operator to condition said power means, independently of said movable device control, to cause said power means to operate, during the ensuing machine cycle initiated while said front-feed means is in open-throat condition, to move said front-feed means to closed-throat condition prior to operation of said printing mechanism and to return it to open-throat condition after said printing mechanism has operated.
14. A front-feed machine of the class described having a motor driving means for giving it cycles of operation, a printing mechanism normally operated at a predetermined time during a machine cycle, a traveling paper carriage supporting a platen, front-feed means for receiving and holding a work sheet in front-fed position relative to said platen, said front-feed means being movable from a closed to an open-throat condition and vice versa, power means for moving said front-feed means, said power means normally being ineffective to move said front-feed means, and manipulative means operable at the option of the operator independently of any movement of, or position of, said carriage for conditioning said power means to enable it, during the ensuing machine cycle initiated while said front-feed means is in open-throat condition, to move said front-feed means to closed-throat condition prior to operation of said printing mechanism and to return it to open-throat condition after said printing mechanism has operated.
15. A front-feed calculating machine of the class described having motor driving means for giving it cycles of operation, a printing mechanism normally operated at a predetermined time during a machine cycle, a traveling paper carriage supporting a platen, said carriage normally moving from one column to another during each machine cycle but being capable of being held stationary, front-feed means for receiving and holding a work sheet in front-fed position relative to said platen, said front-feed means being movable from a closed to an open-throat condition and vice versa, power means for moving said front-feed means, said power means normally being ineffective to move said front-feed means, and manipulative means operable at the option of the operator while said throat is open to cause a cycle of machine operation, to cause said carriage to remain stationary, and to condition said power means to enable it to operate to cause said front-feed means automatically to be moved to closed-throat condition prior to operation of said printing mechanism and to be returned to open-throat condition after said printing mechanism has operated.

ROBERT L. MULLER.
